UNITED STATES PATENT OFFICE.

LEON W. BROWN, OF NEW YORK, N. Y.

BOTTLE-CAP.

1,116,983.

Specification of Letters Patent. Patented Nov. 10, 1914.

Application filed March 16, 1914. Serial No. 825,044.

To all whom it may concern:

Be it known that I, LEON W. BROWN, a citizen of the United States, residing at New York, in the county of New York and 5 State of New York, have invented certain new and useful Improvements in Bottle-Caps; and I do declare the following to be a full, clear, and exact description of the invention, such as will enable others skilled 10 in the art to which it appertains to make and use the same.

This invention relates to new and useful improvements in bottle closures and more particularly to an air-tight bottle cap, and 15 the primary object of the invention is to provide a device of this character which may be quickly and readily applied to use and removed when desired.

A further object of the invention resides 20 in providing a cap or closure which is designed to snap into engagement with the bottle neck when disposed to its closed position whereby to provide an air-tight closure which is not adapted for casual dis- 25 engagement.

Still another object of the invention resides in providing a metal bottle cap having a plurality of yielding tongues or the like thereon for engagement with an external annular groove formed in the bottle neck. 30

A further object resides in providing a device which is simple and durable in construction, inexpensive to manufacture and 35 one which will be very efficient in use.

With these and other objects in view, my 40 invention consists in the novel features of construction, combination and arrangement of parts as will be hereinafter referred to and more particularly pointed out in the specification and claims.

In the accompanying drawing forming 45 part of this application, Figure 1 is a side elevation of a bottle cap applied to use and constructed in accordance with my invention; Fig. 2 is a vertical section therethrough; Fig. 3 is a horizontal section as seen on line 3—3 of Fig. 1; Fig. 4 is a perspective view of my improved closure in a 50 removed position with respect to the bottle neck; and Fig. 5 is a detail perspective view of a slightly modified form of the invention.

In describing my invention, I shall refer to the drawing in which similar reference 55 characters designate corresponding parts throughout the several views and in which,

1 indicates a bottle or vessel of any desired type having a neck 2 thereon, said neck being provided with an external annular groove 3 arranged in a plane slightly below the lip or outer peripheral edge of said neck. 60 A metal cap or closure 4 is provided which fits over the upper or open end of said neck and the side walls of which are designed to project over the outer periphery of the neck to a plane below the plane of the annular groove 3. The inner face of the top of the cap 4 has a resilient disk 5 secured therein which is preferably formed of cork whereby to engage the peripheral edge or lip of the 65 neck and afford air tight connection between the cap and the neck when the former is applied to the latter.

My invention primarily contemplates the provision of a means on a cap for engagement with the annular groove 3 whereby to yieldingly retain said cap in position on the neck and to this end, the wall of the cap or closure 4 adjacent its lower edge is provided with pairs of vertically spaced 70 apart slots 6. These pairs of slots are arranged at regular intervals throughout the periphery of the wall of the cap, there being as many pairs as are found desirable. In the drawing I have shown three sets, 75 but any number more than one may be provided to carry out the object. These slots 6 are enlarged at their ends in double key-hole fashion and the provision of each pair of slots produces a tongue or the like 80 therebetween. The tongue formed between each pair of slots is depressed or struck inwardly centrally of its ends as indicated at 7 thereby providing a plurality of inwardly extending and yielding projections 85 on the cap which are positioned to snap into engagement with the annular groove 90 95 on the neck of the bottle when said cap is applied thereto. In order to permit these inwardly extending and yielding projections 95 on the cap to be engaged with said groove in the bottle neck, this cap or closure must be applied to the bottle neck with considerable force thus causing the cork or other yielding disk 5 in the top 100 thereof to yield considerably as indicated in the section illustrated in Fig. 2 of the drawing. In this manner, it will be seen that the tendency of the cap is to draw upwardly thus causing the projections 7 to 110 bind tightly against the upper wall of the groove 3. In view of these conditions, the

pressure of the cap on the upper peripheral edge or lip of the neck 2, will be so great as to provide positively an air-tight connection between the cap and said neck.

5 From the above description of the construction of my improved bottle cap, it will be seen that by merely applying the cap to the neck of the bottle and forcing downwardly thereon, the inwardly extending and 10 yielding projections 7 will snap into engagement with the annular groove of said neck and securely lock the closure thereon. The cap will then be securely held in place on the bottle and is not adapted for casual 15 displacement. However, the same may be readily removed by grasping the cap and drawing upwardly thereon thus causing the projections 7 to yield for disengagement with the annular groove 3 in which the 20 same are seated. In order to afford a grasping means on the cap or closure so that the same may be readily removed when desired, said cap has the upper portion of the wall thereof corrugated as indicated 25 at 8. With a bottle cap constructed and applied to use in the manner described, it will be seen that an additional cork or closure will not be entirely necessary but the same may be provided if desired.

30 In the shipment of bottles having caps applied thereto constructed in accordance with my invention, it is particularly desirable to provide some means for additionally securing the cap in place so as to prevent 35 any possible disengagement of the cap other than by manual operation. To this end, the wall of the cap or closure 7 is provided with orifices 9 one being arranged on each side of each set of series of slots 6. Dis- 40 posed through each pair of orifices 9 in connection with each set of slots is a wire section 10, the same being disposed across the outer face of the tongue 7 in the depressed portion thereof so as to be also disposed in 45 the groove 3. The extreme ends of each wire section are then bent as shown at 11 to fit flatly against the outer face of the cap and thus the wire is held or secured in position. By so positioning these wires, it 50 will be seen that the inwardly extending and yielding tongues or projections 7 may not be readily disengaged from the annular groove 3 nor may the same be disengaged through manual operation without distort- 55 ing and entirely damaging the cap or closure. It will thus be seen that these wire sections afford a securing means for the cap and after the bottle with its contents is sold to the consumer, these wires may be re- 60 moved.

In Fig. 5 I have shown a slightly modified form of the invention wherein a cap member 12 is provided, the same being slotted as in the first mentioned form to provide pairs of vertical spaced apart slots 13. The pro-

70 vision of these slots, as in the other form, provides tongues or the like 14 therebetween, which tongues are to be depressed about centrally. In the present form however, the metal forming the cap is understood to be such as will not admit of such depression and in order to permit the same to be so constructed as to be readily engaged with the annular groove in the bottle neck, each tongue is slit transversely adjacent its 75 lower end as shown at 15. After being so slit, the tongue may be depressed and bent as shown so as to perform the function of automatically engaging the annular groove in the bottle neck and securing the cap member 80 on the latter. Otherwise, this form of cap is the same as the form above described, it being understood that this form of the invention is necessary when the metal from which the cap is formed is too thick and 85 strong to be readily bent and depressed as shown in the first mentioned form.

90 From the foregoing description of the construction of my improved device, the manner of applying the same to use and the operation thereof will be readily understood and it will be seen that I have provided an improved bottle cap or closure which is simple and durable in construction, inexpensive to manufacture and one which will 95 be very efficient and useful in operation.

99 While I have particularly described the elements best adapted to perform the functions set forth, it is obvious that various changes in form, proportion and in the 100 minor details of construction may be resorted to without departing from the spirit or sacrificing any of the principles of the invention.

Having thus described my invention, what 101 I claim as new is:

1. The combination with a bottle neck having an annular external groove therein arranged in a plane adjacent the open end thereof; of a cap applied to said neck and 110 having a depending peripheral flange thereon extending to a plane below the horizontal plane of said groove, said flange being provided with pairs of vertical spaced apart slots 111 providing tongues therebetween, said tongues being depressed inwardly midway of their ends to provide yielding projections for engagement with the annular groove on said bottle neck, a yielding disk in the top of said cap for engagement with the peripheral edge of said neck, and means insertible through portions of the flange on said cap and engaging the depressed portions of said yielding tongues to secure the latter in place in the groove in said bottle neck.

12 2. The combination with a bottle neck having an external annular groove formed therein in a plane just below the open end thereof; of a cap applied thereto and provided with a depending peripheral flange 13

extending to a plane below the horizontal plane of said groove, said flange being provided with pairs of vertical spaced apart slots providing tongue portions therebetween, said tongue portions being depressed inwardly to provide yielding projections for engagement with the annular groove on said bottle neck, said flange being also provided with orifices arranged on opposite sides of the sets of slots, a yielding disk applied to the inner face of said cap for engagement with the peripheral edge of the bottle neck, and wire sections insertible through the

pairs of orifices of the flange on said cap to extend over the tongues in the depressed portions thereof whereby to secure said depressed tongues in position in the annular groove of said bottle neck. 15

In testimony whereof I have hereunto set my hand in presence of two subscribing 20 witnesses.

LEON W. BROWN.
